UNITED STATES PATENT OFFICE.

PETER G. GIELEN, OF PATERSON, NEW JERSEY.

HARNESS MECHANISM FOR LOOMS.

Application filed May 16, 1921. Serial No. 469,921.

To all whom it may concern:

Be it known that I, PETER G. GIELEN, a citizen of the Republic of France, residing at Paterson, in the county of Passaic and State of New Jersey, have invented certain new and useful Improvements in Harness Mechanisms for Looms, of which the following is a specification.

My invention relates to shedding mechanism for looms, and particularly for looms of the class of that disclosed by my Letters Patent No. 1,362,287, wherein the weaving is done in an upright plane and so the shedding is performed in a more or less horizontal plane. My object is to simplify the construction and increase the efficiency of shedding means for looms of the particular kind mentioned, render the mechanism as compact and space-saving as possible, and arrange and construct the parts thereof so as to require the least amount of attention for repairs and replacement of parts and so that when such replacements are necessary, as in the case of the breaking of a hook, they may be effected with facility and the minimum loss of time.

In the drawings,

Figure 1 is a front elevation of the improved harness mechanism;

Figure 2 is a left or outer side elevation thereof, partly broken away;

Figure 3 is a rear elevation;

Figure 4 is a horizontal section taken just above the main supporting plate;

Figure 5 is a side elevation of the lower portions of the hook-actuating levers or knives and the cams for controlling their movements; and

Figures 6 and 7 are rear elevations of said lever portions and the cams, showing them in two different positions.

Let *a* in the drawings represent a tappet shaft corresponding to the shaft 18 in my aforesaid patent. *b* is an upright which is to be bolted to the frame of the loom shown in said patent back of the shaft *a*, forming therewith a part of the main supporting structure.

c is a casting in the form of a plate-like piece having a rearwardly extending flange *d* at its lower edge formed with longitudinal slots *d'* out of alignment with each other. The thus flanged plate is secured to the upright *b* by brackets *e* provided on the upright, the plate projecting laterally therefrom and consequently from the loom. To

the back of the plate are secured two vertical strips or elongated blocks *f* and *g*, the former being arranged at or near the inner edge of the plate and the other more or less near its outer edge; the thickness of the strip or block *f* from the plate rearwardly is greater than that of the strip or block *g*. These two pieces are provided from top to bottom with slots *f'* *g'* which extend horizontally from the rear face of the plate rearwardly but so as to afford stops *f''* *g''* at their rearward or outward ends, the depth of the slots *f'* being of course somewhat greater than that of the slots *g'*.

The thus comb-like or slotted strips or blocks *f* *g*, whose slots are aligned with each other, receive in their corresponding slots substantially U-shaped elastic hooks or actuators *h*, the legs of which have their terminal portions bent outwardly (in the present case) to form hooks *h'* *h''*, and that leg which has the hook *h'* being somewhat shorter than the leg which has the hook *h''*. Two sets *i* of sheaves suitably journaled on vertical axes in the supporting structure of the loom are arranged one at the left and the other at the right back of the harness shafts *j*, which are arranged to slide in horizontal planes in said supporting structure substantially the same as in my said patent, being normally drawn toward the front of the loom by springs *k* and being adapted to be moved against the tension of the springs by cords *l* extending around the sheaves and attached to the actuators *h*.

A bracket *m* projects outwardly from the upright *b* in a plane somewhat back of and parallel with the plane of the plate *c*, being bolted to the upright. Pivoted to and suspended from this bracket are two levers *n'* *n''* which at their lower end carry rolls *o* bearing against the left hand faces of cams *p'* *p''* fixed on the shaft *a*; these cams are reverse counterparts of each other in that the left-hand or acting face of the cam *p'* has two diametrically opposite falls or depressions whereas the corresponding face of the cam *p''* has diametrically oppositely rises, the depressions of cam *p'* registering with the rises of cam *p''*. The springs *k*, acting through the harness shafts, the cords *l*, and the actuators *h*, one hook of each of which at least is, in the normal operation of the mechanism, engaged with one of the levers, hold the levers against the cams. When the cams are in the position shown in Fig. 6

(compare Fig. 4) the harnesses will be leveled in vertical alinement; when they are in the position shown in Fig. 7 some of the actuators will have been drawn to the right 5 by the corresponding springs *k* and the others drawn to the left by the lever *n'*, the shed being then open.

- The plate *c* has projecting forward therefrom a grid *q* in depending brackets *q'* of 10 which is journaled, parallel with the plate, the horizontal shaft *r* of a drum *s* carrying a pattern chain *t*, the drum being adapted to be rotated from any rotating part of the loom through a wheel *u* on the shaft. The 15 pattern chain actuates levers *w* pivoted in the grid above and resting on the chain, whose pegs *t'* elevate them as they pass. Arranged in the slots of the grid on a horizontal shaft *x* are the bell-crank levers *y* 20 whose horizontal arms have set-screws *z* resting on the levers *w*. The free ends of the upstanding arms of the levers *y* are bent rearward, being arranged at graduated elevations, and when these levers are actuated 25 by the pattern chain they press rearwardly other levers 2 fulcrumed on a vertical shaft 3 secured in bosses 4 projecting forwardly from plate *c*. The plate has attached to the front face thereof a strip or elongated vertical block 5 provided with a vertical series 30 of holes in which are arranged push-pins 6 whose head 6' are notched to receive and thus support the free ends of the levers 2; this block is opposite the block *g* and its 35 holes are opposite the slots in said block and so when any lever *y* is actuated the movement is transmitted through the corresponding push-pin to the relatively forward or longer leg of the corresponding actuator *h*. 40 The elasticity of the actuators normally maintains the legs of each in about the position shown by full lines in Fig. 4: that is, the hook on the rear leg of each actuator is always in the same plane as the knife or lever *n''*, but the hook on the other leg normally tends to stand forward of the plane 45 of movement of the other knife or lever *n'*. 50 The operation will be readily understood by those skilled in the art. When the shaft *u* is in rotation the levers *n' n''* are moved alternately toward and from each other twice for every revolution (that is, once for each pick) of the loom; the drawings show the levers in Figs. 1, 3, 4 and 6 in the positions 55 where they are closest together, the shed being closed. If none of the actuators were therefore "called" from the pattern chain (which is timed to occur when the shed is closed), on the ensuing movement 60 of the levers apart all the actuators, being then engaged only with the lever *n''*, would travel to the right therewith, allowing the harness shafts to move forward under the pull of the springs *k*. But to form the shed 65 some of the actuators are "called" from the

pattern chain, that is, through the parts *w*, *y*, 2 and 6, the forward legs of the called actuators being pressed or sprung back so that their hooks come into the plane of movement of the lever *n'*, wherefore the actuators so called will be moved to the left as the remaining actuators are allowed to move to the right, so that some of the shafts recede as the others go forward. Bodily movement of each actuator backward when called, i. e., without the forward leg springing backward relatively to the rearward leg, is prevented by the latter leg bearing at this time against the stop *f* corresponding thereto.

When the levers *n' n''* are closest together they are substantially parallel; but when they are moved apart each is inclined (Fig. 3, dotted lines), in consequence of which in the latter positions of the levers the harness shafts from top to bottom will be spaced regularly increasing distances, thus to bring the portions of the warps between the harness shafts and fell of the cloth in two distinct converging planes. The degree of convergence may be varied by shifting the bracket *m* vertically in a slot *m'* provided therefor in the upright *b* and shifting the bearings of the rollers *o* vertically in slots *o'* provided therefor in the lever *n' n''*.

The improved mechanism is efficient, compact and durable. If an actuator breaks or becomes distorted it can be readily removed for repairs or replacement by a new one by springing its legs together and withdrawing it from the slots of the blocks *f g*.

I do not wish to be limited to the specific arrangement and construction of the several parts except as provided in the appended claims:

I claim:

1. In combination, with a plate-like support, a set of back-and-forth movable actuators each arranged close to and movable parallel with one broad face thereof, said support having means to guide the actuators, means to move the actuators back and forth including a knife movable back and forth substantially parallel with said face, said actuators having portions thereof movable into and out of the path of movement of the knife, and means, arranged on the support opposite and close to its other broad face and having parts thereof penetrating said support, for selectively controlling the movements of said actuators into and out of the path of movement of the knife.

2. In combination, back-and-forth longitudinally movable bifurcated elastic harness actuators, the several actuators being arranged with the legs of each in a plane parallel with that of the legs of any other actuator, a plate-like support having means

on one broad face thereof to confine each actuator to substantially its said plane and means to resist movement of one of its legs transversely relatively to the other while permitting the other leg to be sprung transversely thereof, means to move the actuators longitudinally back and forth including a knife movable back and forth substantially parallel with said face of the support, said other leg of each actuator having a lateral projection movable in the transverse movement of said leg into and out of the path of the knife, and means, arranged on the other broad face of said support and having parts thereof penetrating the same, for selectively controlling the transverse movements of said other legs of the actuators.

5

3. In combination, back-and-forth longitudinally movable bifurcated elastic harness actuators, a plate-like support having an

elongated member across one broad face thereof formed with transverse slots substantially perpendicular to said face and each affording an outward stop, said actuators being guided in said slots and held thereby in parallel planes and adapted to bear with one leg of each against the corresponding stop when the other leg is pressed away from the support, means to move the actuators longitudinally back and forth including a knife movable back and forth substantially parallel with said face of the support, said other leg of each actuator having a lateral projection normally arranged in the path of the knife, and means on said support for selectively moving said other legs of the actuators away from said support.

In testimony whereof I affix my signature.
PETER G. GIELEN.
